APPARATUS FOR TIMING WATCHES

Arthur Jay Auble, Ord, Nebr.

Application August 3, 1940, Serial No. 350,834

1 Claim. (Cl. 73—52)

My invention relates to improvements in an apparatus for timing watch movements relative to a master chronometer, and the primary objects in view is to provide a simple and efficient apparatus which greatly simplifies and speeds up accurate regulating of watch movements.

Other important objects and advantages of my invention will be apparent from a reading of the following description taken in connection with the drawings, wherein for purposes of illustration I have shown a preferred embodiment of my invention.

In the drawings:

Figure 1 is a general front elevational view of an apparatus or system of this character.

Figure 2 is a top plan view of the watch movement holder and loud speaker.

Figure 3 is a right hand side elevational view of Figure 2.

Figure 4 is an enlarged rear elevational view of the watch movement clamp.

Figure 5 is a fragmentary plan view showing the escapement wheel and escapement lever of the master watch or chronometer and showing the electrical contacts and connections therein involved.

Figure 6 is an edge elevational view of Figure 5.

Figure 7 is a plan view of the escape wheel and escapement lever mechanism of a watch movement to be tested and showing the electrical contact arrangements therein involved.

Figure 8 is an edge elevational view of Figure 7.

Figure 9 is a schematic wiring diagram showing the electrical association of the master chronometer and compared watch movement contacts and their connections with the loud speaker and the source of electrical energy.

Referring in detail to the drawings, the numeral 5 designates a suitable casing for containing a battery 6 and having on the front wall thereof a hook 7 over which is passed the ring 8 on the master watch or chronometer 9. One terminal 10 of the said battery has connected thereto a wire 11 which leads through the side of the casing of the master watch 9 and is suitably connected to a banking pin 12 adapted to form a part of the escapement of said master watch and to be engaged by the escapement lever under movement thereof in one direction the escapement lever 13. The escapement lever 13 is operated by the escapement or escape wheel 14. The banking pin 12 which is screwed into the plate of the watch has thereby electrical connection with the plate through the plate with

the wire 11. The remaining terminal 17 of the said battery is connected by a wire 18 to one terminal 19 of the loud speaker 20 which has trunnions 21 connecting into the upper ends of a semi-circular bracket 22 which rises from the upper end of a pedestal 23 whose lower end is connected to the approximate middle of the three-quarter circular base 24 which like the casing 5 is adapted to rest on a supporting surface 25. The remaining terminal 26 of the loud speaker is connected by the wire 27 with the wire 28 which is electrically connected in a manner presently described to the escapement lever of the compared watch movement 29 while the compared watch movement is being tested.

Rising from the top of one horn of the three-quarter circular base 24 is the vertical arm 30 of insulation material whose upper part is traversed by the bolt 15 of the watch clamp 16. The watch clamp comprises a substantially three-quarter circular spring metal band 31 whose approximate center is traversed by the bolt 15 and which has radially inwardly extending arms 32 and 33 of triangular shape and provided on the hypotenuse side thereof with steps 34 to accommodate different sized watch movements in conjunction with the similarly formed arm 35 positioned in extension of the bolt 15 as illustrated in Figure 4.

Supported to extend forwardly from the region of the arm 35 and bolt 15 is the non-conductive arm 36 through which extends at right angles and also in a horizontal position the conductive wire 28 already mentioned. The wire 28 has adjacent its free end a sleeve 37 to which is connected the forward end of a small gauge spring-wire coil 38 whose opposite end electrically engages the pivot 39 of the escapement lever 13a of the compared watch movement being regulated. The expansion of the coil 38 presses its terminal point sufficiently into engagement with the escapement lever pivot 39 to make adequate electrical connection. The sleeve 37 is adjustable along the conductive wire 28 to enable properly positioning the spring 38. As shown in Figure 8, the upper and lower pivots of the lever 13a are insulated at 40 and 41, respectively, by their plate jewels.

Referring now to the master watch contact arrangement shown in Figures 5 and 6, it is to be noted that on the opposite side of the escapement lever 13 is a second contact 42 which like the contact 12 is in the nature of a banking pin, with the escapement lever swinging between these contacts and at the end of its opposite

strokes to engage the corresponding one of these contacts. It is also to be observed that the pivots of the lever 13 are insulated as indicated by the numerals 43 and 44, respectively, from the master watch movement. It is also to be observed with respect to the contact 42, the banking pin such as constitutes the contact 12 is removed, and in its place is inserted a roller jewel 45 so that the engagement of the lever with it makes no electrical connection such as takes place when the lever engages the contact 12. A hair spring 46 is circumposed on the lever staff 47 below the lever 13 and has one end thereof connected to the said staff and the other end thereof to the wire 14' which leaves the watch movement without electrical contact therewith.

In the compared watch contact arrangement shown in Figures 7 and 8 the contact 12a is insulated from the watch movement by a suitable insulating preparation painted on it, so that the engagement of the escapement lever 13a with it produces no electrical connection. The lower contact 42a is uninsulated, so that electrical connection is made when the lever 13a engages the banking pin 42a.

Referring now to Figure 9, it will be apparent that the wire 14' leading from the hair spring 46 on the master watch movement leads to the contact 42a of the compared watch movement, while the wire 27 leads from the spiral spring 38 of the compared watch movement to the terminal 26 of the loud speaker, the remaining side of the loud speaker being connected by the wire 18 as already explained, with one terminal of the battery 6, whose remaining side is connected to the contact 12 of the master watch contact arrangement.

It is obvious that the current coming from the battery passes to the plate of the master watch movement to the contact 12 and to the lever 13 of the master watch movement when the lever 13 engages the contact 12, the current then passing by the wire 14' to the compared watch movement, passing through the plate or frame of the movement and to the contact 42a and thence via the wire 27 to the loud speaker 20 whose remaining side is connected to the battery 6. It is also obvious that different combinations of positions of the levers 13 and 13a, with resultant engagements with the respective contacts 12 and 14a at different times and at different intervals, will produce correspondingly different signals in the loud speaker 20. Because of the arrangement, a variation of from $1/200$ to $1/500$ of a second may be detected between the compared watch and the master watch or chronometer.

If $1/100$ of a second is the normal length of time

that the escapement levers 13, 13a of the watches are in engagement with their respective banking pin contacts, the maximum period of time between making and breaking the loud speaker circuit would be $1/100$ of a second and would occur when the two levers were exactly in phase. Such making and breaking of the circuit would produce two clicks in the loud speaker spaced $1/100$ of a second apart. These two clicks would be followed by a period of silence until the levers 13, 13a again made contact with their respective banking pin contacts. If the two watches were running at exactly the same rate, two more loud speaker clicks spaced apart $1/100$ of a second would again be produced. If the watch being compared were gaining or losing, the levers 13, 13a would not return to their respective banking pin contacts at exactly the same instant, the period during which they were both in contact with the banking pin contacts would decrease and the loud speaker clicks would be spaced less than $1/100$ of a second apart. This period would decrease until one lever was lagging more than $1/100$ of a second behind the other lever, at which time one lever would leave its banking pin contact before the other arrived and no loud speaker clicks would be produced. There would then follow a relatively long period of silence until one lever gained substantially a complete cycle on the other, at which time another series of two closely spaced clicks would again be produced.

Although I have shown and described herein a preferred embodiment of my invention, it is to be definitely understood that I do not wish to limit the application of the invention thereto, except as may be required by the scope of subjoined claim.

Having described the invention, what is claimed as new is:

40 A system for timing watches comprising a master watch, a pair of electrical terminals connected to said master watch, means for momentarily electrically connecting said terminals in response to each oscillation of the escapement lever of said watch, a pair of electrical terminals for connection to a test watch, means for momentarily electrically connecting said test watch terminals in response to each oscillation of the 45 escapement lever of said test watch, a source of electrical energy, an electrical signal device and means for connecting said test watch terminals in series with said master watch terminals, said source of electrical energy and said signal device, 50 whereby the circuit is completed through said signal device only when the escapement levers of the master and test watch are in a given phase relationship.

ARTHUR JAY AUBLE.
